UNITED STATES PATENT OFFICE.

ERASMUS A. POND, OF RUTLAND, VERMONT.

IMPROVEMENT IN PILL-MAKING MACHINES.

Specification forming part of Letters Patent No. 9,455, dated December 7, 185 .

To all whom it may concern:

Be it known that I, ERASMUS A. POND, of Rutland, in the county of Rutland and State of Vermont, have invented certain new and useful Improvements in Machinery for Making Pills; and I do hereby declare that the following is a full, clear, and exact description of the same, reference being had to the accompanying drawings, forming part of this specification, in which—

Figure 1 is a side elevation of one of my improved pill-making machines. Fig. 2 is a vertical section of the same. Fig. 3 exhibits one of the mold-rollers detached from the machine. Fig. 4 is a section of the parts of the two mold-rollers which are in contact.

Similar letters of reference indicate corresponding parts in each of the several figures.

This invention consists in the employment of two cylinders having a number of recesses in their peripheries, the said recesses being of hemispherical form or of the form of half the pills, and at corresponding distances apart in each cylinder, and the cylinders being placed parallel with each other with their peripheries nearly touching, and being geared together in such a manner that the recesses in each match or register with the recesses in the other, and that they will revolve in opposite directions. The pill mass is fed between the cylinders by a pair of feed-rolls, and, being pressed into the recesses, is formed into pills. In order to prevent the pills remaining in the recesses and to insure their being disengaged from the cylinders, a small roller is placed parallel with each cylinder, and an endless band of thin india-rubber or other elastic material of sufficient width to cover all the recesses passes round the cylinder and small roller. This band moves with the revolution of the cylinder, and is pressed into the recesses by the pill mass as it is formed into pills; but after the molds pass each other and the pressure is removed, the band springs out of the molds and expels or delivers the pills.

To enable others skilled in the art to make and use my invention, I will proceed to describe its construction and operation.

A is the frame of the machine.

B B are the mold-cylinders, whose journals b b are fitted to suitable bearings in the frame.

The two cylinders shown are just alike, each having the same number of recesses a a, similarly arranged. It is intended that the recesses shall be as close as possible together, so as to have the greatest number possible in one pair of cylinders. The toothed wheels L L, by which the cylinders are geared, have each the same number of teeth, so that they revolve at the same speed.

C C are the feed-rolls, which are placed at a short distance apart, above and parallel with the mold-cylinders. Their journals c c fit in suitable bearings in the frame, and they are geared together by a pair of toothed wheels, D D. The mold-cylinders and feed-rollers are driven by gearing from a shaft, E, which is turned by a crank, F, a toothed wheel, G, on the said shaft gearing into one of the wheels D D and into a smaller wheel, H, on the axle of one of the mold-cylinders. The wheel H is so proportioned as to drive the mold-cylinders faster than the feed rolls.

The elastic bands I I are shown in Figs. 1 and 2, and also in Fig. 4, in red color, for the sake of clearer identification. The rollers J J, round which they pass, have their axes fitted in suitable bearings in the framing. Under the mold-cylinders there is an inclined trough or chute, K, into which the pieces fall and down which they are conducted into any suitable receptacle. The pill mass is placed above the feed-rollers and is drawn through them, by which it is reduced to sheets of suitable thickness to make the pills, and pressed down to the mold-cylinders. By the revolution of the cylinders the matching-recesses are placed, and as they come in contact each matching pair forms a perfect mold and form one pill.

The manner in which the elastic band operates is shown in Fig. 2, where it is shown at e pressed into the recesses a a, and entirely surrounding or incasing the pill. At f the mold is shown open, and the pill is just being expelled from the recess. The recesses and band are shown in the last place in dotted lines, as the mold there represented is not in line with the one above it. The molds are out of line circumferentially for the purpose of using the whole width of the sheet of pill mass.

Fig. 4 shows a whole row of molds filled.

What I claim as my invention, and desire to secure by Letters Patent, is—

1. Molding or forming pills by means of two cylinders, B B, having each a number of recesses, *a a*, in its periphery, the recesses in one cylinder matching with those in the other, and each matching pair forming a mold of the required form of the pill, the said cylinders revolving in opposite directions, and the pill mass being conducted between them, substantially as herein described.

2. The bands II, of india-rubber or any suffi-

ciently elastic material, passing round or partly round the mold-cylinders, for the purpose of expelling the pills from the recesses *a a* after the molds are open, substantially as herein set forth.

ERASMUS A. POND.
